ALARM CLOCK MOVEMENT

Helmut Junghans, Schramberg-Sulgen, Eckenhof, Germany; vested in the Alien Property Custodian

Application October 14, 1940, Serial No. 361,148
In Germany August 30, 1939

2 Claims. (Cl. 58—16)

This invention relates to an alarm clock movement, and has for its object to prevent return motion of the alarm setting spindle.

In the known alarm clock works in which the alarm locking or click spring is controlled by a member attached to the alarm setting wheel and having a notch cooperating with a catch, the alarm setting spindle must be rotated in one direction only so as to insure relative displacement of the attached member and the catch in the same direction. If the spindle is turned in opposite direction, the catch strikes the inclined edge of the notch in the attached member and during further rotation the clock movement is driven backward by the intermediate gears. Due to the gearing up in the clock movements, the frictional resistance is usually so great that the alarm setting means will break.

Various proposals have been made to prevent return motion of the alarm setting spindle in a positive manner, and one of them provides for instance a screw-on setting knob which will unscrew from the end of the setting spindle when an attempt is made to turn the latter in the wrong direction. This arrangement is, however, open to the objection that the knob is often lost and two kinds of knobs and fastening means are required for the alarm setting and the minute spindles.

It has further been suggested to interpose clutch couplings between the alarm setting spindle and the toothed wheel supporting the attached member mentioned, but the practical application of this suggestion was found to require too many additional structural elements.

According to the invention, the difficulties are eliminated by connecting the alarm setting spindle with a fixed point of the clock through the medium of a Schwarz coupling spring which is of the volute type and so wound upon a plain shaft as to hug it with a certain initial tension. One end of this spring has a tangential continuation which is engaged by an alarm shut off lever, and the other end thereof is anchored at the fixed point on the frame of the mechanism close to the shaft. Notwithstanding its small dimensions in the present instance, a coupling spring of this type is capable of transmitting relatively great forces and of offering so great a resistance to any attempt to turn the alarm setting spindle in the wrong direction that instant and effectively attention is called to this faulty manipulation without injuring the clock.

The use of such a coupling spring for the alarm

setting spindle affords the advantage that the alarm setting knob like the hand setting knob can be secured to its spindle by means of a square end thereon and that both knobs can be made alike and interchangeable. In clocks provided with the widely used shut off members which upon winding the alarm driving spring are disengaged from the alarm escapement wheel by a restoring spring, the Schwarz coupling spring on the alarm setting spindle may serve also for another purpose. Instead of cutting off one end thereof as mentioned, it is allowed to stand out from the spindle and to act thus as restoring spring for the alarm stop. The coupling spring is preferably initially tensioned when installed between the alarm stop and the fixed point of the clock.

One form of the invention is illustrated by way of example in the accompanying drawing, in which

Figure 1 is a front view of alarm setting and stopping parts according to the invention; and

Fig. 2 is a top view thereof.

a is the alarm setting spindle, *b* the hand setting spindle, *c*₁ is the front plate and *c*₂ the rear plate, in which plates the two spindles and the other parts of the clockwork are arranged. *d* is the dial, and *c* designates the back wall of the casing. On the alarm setting spindle *a* a pinion *f* is disposed which engages the alarm setting wheel *g* having an attachment *g*₁. *h* is a toothed wheel which is rotated once every 12 hours through intermediate gears, not shown, and which is firmly connected with the hour-hand *i*. The wheel *h* cooperates in known manner with the alarm locking spring *k* and also with the attached member *g*₁ through the nose or catch *h*₁. From the alarm escapement wheel *l* the hammer rod *m* is driven in the usual way. *m*₁ is the stop arm cooperating with the locking spring *k*, and *m*₂ is the hammer.

The stop lever *n* is freely and oscillatably disposed on the spindle *a* with the aid of two perforated flaps *n*₁ whose distance apart corresponds to the width of the frame. Through its arm *n*₂ it can engage the escapement wheel *l* in known manner, and its arm *n*₃ is engaged by the shut off knob *o*.

A Schwarz coupling spring *p* is closely wound upon the alarm setting spindle *a* with initial tension. One end of the spring, designated *p*₁, engages a hole *c*₁₁ of the front plate *c*₁ so as to effect a coupling between the spindle *a* and a fixed point of the clock. The other end *p*₂ of the spring *p* lies on a continuation *n*₄ of the stop lever *n*. The spring *p* is arranged with initial tension

between the plate c_1 and the stop lever n in such manner that the lever n is subjected to spring pressure which urges it into releasing position. Both setting spindles a and b are provided with square ends a_1, b_1 of the same dimensions to which similar setting knobs q, r are attached. The coupling spring p is built in so that the spindle a can be turned only in the direction of the arrow s , Fig. 1.

The alarm setting shaft a is turned by the knob q until the alarm hand t , which is fast with the gear wheel g in mesh with the pinion f , is at the desired setting on the alarm dial. This rotation of the shaft a is counterclockwise. If it be attempted to rotate the shaft a clockwise, the coils of the spring p , owing to frictional engagement of the shaft therewith, will be caused to wrap more firmly about the shaft and oppose such clockwise rotation thereof in a manner preventing damage to the mechanism.

The alarm is released as follows. In the running of the clockwork, the minute hand shaft b , through gearing not shown, is rotated. The wheel h with the lug h_1 is fast on this shaft b . The alarm stop spring k presses the lug h_1 against the attachment g_1 on the alarm setting wheel which attachment g_1 has a notch, not shown, the position of which depends on the setting of the alarm hand. The shaft b can move axially to a certain extent in the frame plates c_1, c_2 . When the wheel h with the lug h_1 has rotated until the latter is opposite the said notch in the attachment g_1 , the lug h_1 by the action of the spring k and axial movement of shaft b engages the notch. This results in the offset end of the spring k being pushed towards the dial d (Fig. 2), releasing the hammer arm m_1 , whereby the wheel l can rock the alarm hammer m_2 to and fro.

To shut off the alarm, the shut off knob o is pressed inwards and its conical point forces the stop lever arm n_3 upwards against the action of

the spring end p_2 , and the point n_2 of the lever n enters a tooth gap of the escapement wheel l . The next tooth of this wheel now holds the lever n in known manner, and in engagement with the 5 wheel teeth, since the full strength of the alarm spring is operative thereon. Upon removing the finger from the knob o the latter returns to normal position as shown in Fig. 2.

The return of the stop lever n to initial position is effected in known manner merely by winding the alarm spring. This releases the pressure of the escapement wheel l on the point n_2 of the lever n enabling the latter under the action of the spring end p_2 to return in counter-clockwise direction to release position.

What is claimed is:

1. Alarm clock mechanism comprising a frame, alarm release setting means including a member intended for rotation in one direction only, an 10 alarm hand setting stem rotatably mounted in said frame and operatively connected to said member, a coil spring tensioned around said stem and frictionally engaging the same said spring having one of its ends fixed to said frame and 15 being arranged to be de-tensioned to free said stem when the latter is rotated in the proper alarm hand setting direction but to be tightened around and lock said stem when the latter is turned in the wrong direction, a tangentially extending portion at the other end of said coil 20 spring, an alarm winding spring, and an alarm shut off lever held in alarm shut off position by the action of said winding spring and released upon winding up said winding spring, said shut 25 off lever being urged into release position by said tangentially extending spring portion.

2. Alarm clock mechanism according to claim 1 in which the alarm shut off lever is pivotable on the alarm hand setting stem.
